VOICE BUILDER

Filed March 9, 1929

Fig. 1.

UNITED STATES PATENT OFFICE

RALPH O. BONELL, OF KENOSHA, WISCONSIN

VOICE BUILDER

Application filed March 9, 1929. Serial No. 345,709.

This invention relates to an instrument adapted to be used for the purpose of cultivating the speaking and the singing voice, and has for one of its objects to provide a novel instrument through the medium of which—since the nasal and head cavities are resonating chambers of the greatest importance and resonance determines the quality and carrying power of every tone—the student may be taught in a simple manner and in a comparatively short time how to properly use these resonating chambers.

With the foregoing and other objects in view, the nature of which will appear as the description proceeds, the invention consists in the construction, combination and arrangement of parts hereinafter fully described and claimed, and illustrated in the accompanying drawing, wherein:

20 Figure 1 is a view partly in top plan and partly in horizontal section of the instrument;

Figure 2 is a view illustrating the manner in which the instrument is to be used, the instrument being shown in vertical section;

25 Figure 3 is a sectional view taken on the vertical plane indicated by the line 3—3 of Figure 2;

Figure 4 is a perspective view of the vibrator of the resonance chamber of the instrument, and

30 Figure 5 is a view in end elevation of the resonance chamber of the instrument.

The instrument comprises a tube 1 which gradually increases its diameter in the direction of its front end and terminates in the bell 2. A mouthpiece 3 is telescopically associated with the tube 1 so as to permit it to be adjusted forwardly and rearwardly with respect thereto and thus enable the effective

40 length of the tube to be varied.

A resonance chamber 4 is arranged at the upper side of the tube 1 and extends transversely thereof. While the chamber 4 may be of any desired formation, it is shown as cylindrical, and is provided at its lower side with the boss 5. An annular flange 6 extending upwardly from the upper side of the tube 1 about an opening 7 formed in said side of the tube 1, receives the boss 5 which together

45 with the flange 6 serves to detachably connect

the chamber 4 to the tube 1. The boss 5 is provided with an opening 8 which establishes communication between the tube 1 and chamber 4. A tongue 9, which is made from thin hard metal, is of arcuate formation in elevation and has a plan contour simulating that of the human tongue, is arranged within the chamber 4 in spaced concentric relation to the lateral or curved wall 4^a of the chamber, and with its side edges in spaced relation to the end walls 4^b and 4^c of the chamber. The tongue 9 is provided at one end with radially offset lugs 9^a which are secured to the wall 4^a of the chamber 4 and support the tongue with its ends arranged at opposite sides of the opening 8 and in spaced relation to the lower side of said wall of the chamber.

45 The chamber 4 is provided in the rear side of its lateral wall with openings 10 and 11, and connected to the chamber in communication with said openings are tubes 12 and 13, respectively. These tubes extend rearwardly in divergent relation from the chamber 4, and are provided at their rear ends with nipples 14 and 15 which are adapted to be inserted into the nasal passages. The nipples 14 and 15 are carried by the upper ends of angular tubes 16 and 17, respectively, which are telescopically associated with the tubes 12 and 13 in order to permit the effective

50 length of the latter tubes to be varied. The tubes 16 and 17 extend downwardly and then upwardly from the tubes 12 and 13 so as to so arrange them with respect to the mouthpiece 3 as to permit this part and the nipples 14 and 15 to be readily applied to the lips and inserted in the nasal passages, as shown in Figure 2. To close the outer ends of the nasal passages, the tubes 16 and 17 are provided with flanges 18 and 19, respectively, which contact with the nose in surrounding relation to said ends of the nasal passages. To permit it to be conveniently supported in position for use, the instrument is provided with a handle 20 which is arranged at the lower side of the tube 1.

55 The lateral wall 4^a and end wall 4^b of the chamber 4 are imperforate, while the end wall 4^c thereof is provided with an opening which is closed by a door 21.

is hinged, as at 22, and is secured in closed position by a latch which permits the vibration of the door and consists of a pin 23 carried by the wall 4^e and a spring strap 24 carried by the door and provided with an opening for the reception of the pin.

It is now recognized that the singing and speaking voices are identical, produced by the same organs in the same way, and developed by somewhat the same training. It is also recognized that resonance determines the quality and carrying power of every tone, and is therefore the most important element in the training of the voice.

It is further recognized that nasal resonance is the most important resonance that when the vibrations are strong in the nasal chamber of the student they are correctly induced elsewhere, and that the power and largeness of tone depend to a great extent upon the right use of the nasal resonating chamber. My instrument is adapted to permit the student to be taught how to properly use his or her nasal chamber in a comparatively short time. When the instrument is in use, the tube 1 and resonance chamber 4 communicate with the mouth, throat, and the nasal chamber with the result that when special exercises are sounded the air in all these parts is vibrated. The vibrations set up in the nasal chambers travel through the tubes 12 and 13 into the resonance chamber 4 and around the tongue 9, some of them enter the tube 1 by way of the opening 8, and the remainder return to the nasal chamber by way of the tubes 12 and 13. The vibrations being amplified and reinforced in the resonance chamber 4 of the instrument pass back into the nasal chamber and then into the mouth. The vibrations set up in the mouth and throat together with other induced vibrations pass through the mouthpiece 3 and out through the bell 2. The nasal chamber vibrations and the mouth and throat and other vibrations are blended in such a manner as to produce the desired tone. This instrument provides a detachable cavity, which, when resonance is established—noticeable by vibrations of the door 21 in the chamber 4—said instrument can be removed at will, thus conveying to the student the idea and feeling of true nasal resonance. Therefore when resonance is established in chamber 4 it must be previously and correctly established in the nasal cavities or chambers of the student. It has been found in practice that it requires but a comparatively short time for the student to employ the nasal chamber to the best advantage, and obviates the present objectional practice of closing the nostrils of the student by the fingers.

In addition to developing the natural and correct use of the voice in a comparatively short time, the instrument corrects faulty

production, singing and speaking through the nose and the like. It also corrects muscular interference and eliminates obstructions of the nose in general, develops breath control, develops freedom of the vocal cords and throat, develops a properly relaxed lower jaw, and produces a tone that is practical in voice training and individually beautiful.

While I have described the principle of the invention, together with the instrument which I now consider to be the best embodiment thereof, it is to be understood that the instrument shown is merely illustrative and that such changes may be made as desired as fall within the scope of the invention as claimed.

What I claim is:

1. An instrument of the character set forth, comprising a tube having a mouthpiece, a resonance chamber, and means adapted to connect the resonance chamber with the nasal passages.

2. An instrument of the character set forth, comprising an adjustable tube having a mouthpiece, a resonance chamber, and adjustable means adapted to connect the resonance chamber with the nasal passages.

3. An instrument of the character set forth, comprising a tube having a mouthpiece, a resonance chamber, a tongue arranged within the resonance chamber, and means adapted to connect the resonance chamber with the nasal passages.

4. An instrument of the character set forth, comprising a tube having a mouthpiece, a resonance chamber communicating with the tube, a tongue within the resonance chamber, the tongue being spaced from the lateral wall of the resonance chamber and having its ends arranged at opposite sides of the point of communication between said chamber and tube, and means adapted to connect the resonance chamber with the nasal passages.

5. An instrument of the character set forth, comprising a tube having a mouthpiece, a cylindrical resonance chamber arranged upon and extending transversely of the tube, the resonance chamber being provided in its lower side with an opening communicating with the tube, an arcuate tongue arranged within the resonance chamber in spaced relation to the lateral wall of said chamber and with its ends arranged forwardly and rearwardly beyond said opening, tubes communicating with the rear side of the resonance chamber, and nipples carried by the tubes.

6. An instrument of the character set forth, comprising a tube having a mouthpiece, a resonance chamber having a vibrating door and means adapted to connect the resonance chamber with the nasal passages.

7. An instrument of the character set

forth, comprising a tube having a mouth-piece, a resonance chamber having an opening in a wall thereof, a hinged door closing the opening, and a latch for holding the door in closed position.

5 In testimony whereof I affix my signature.

RALPH O. BONELL.
